US00D768955S

(12) **United States Design Patent** (10) **Patent No.:** **US D768,955 S**
Lucero (45) **Date of Patent:** **** Oct. 18, 2016**

(54) INSERT FOR A PREKNOTTED ADJUSTABLE NECKTIE	3,999,222 A	12/1976	Walborn	
	4,573,219 A	3/1986	Hooten	
	5,035,002 A	7/1991	Knight, Jr.	
	5,084,916 A *	2/1992	Austin	
			A41D 25/02	
			2/149	
(71) Applicant: Adam Lucero , Las Vegas, NV (US)	5,216,757 A	6/1993	Dorkin	
(72) Inventor: Adam Lucero , Las Vegas, NV (US)	5,295,270 A *	3/1994	Phillips	
			A41D 25/16	
			2/144	
(**) Term: 14 Years	5,416,926 A	5/1995	Koy	
(21) Appl. No.: 29/499,176	D383,887 S *	9/1997	Pehr	
(22) Filed: Aug. 12, 2014	D411,575 S *	6/1999	LaBorde	
	D420,201 S *	2/2000	Azhar	
	6,305,025 B1	10/2001	Pilon	
	6,412,673 B1	7/2002	Chuang	
	D476,134 S *	6/2003	Miller	
	6,687,915 B2 *	2/2004	Kear	
			A41D 25/025	
			2/148	
	6,920,642 B2	7/2005	Dickens	
	D550,929 S *	9/2007	Cordonier	
			D2/600	
			(Continued)	
(63) Continuation-in-part of application No. 13/770,021, filed on Feb. 19, 2013, now Pat. No. 8,931,116, and a continuation-in-part of application No. PCT/US2014/011215, filed on Jan. 13, 2014.
